UNITED STATES PATENT OFFICE.

DAVID J. SEAMAN AND CHARLES F. SOMMERS, OF SAGINAW, MICHIGAN.

MEANS FOR CARRYING CARDBOARD BOXES.

Application filed June 14, 1924. Serial No. 719,976.

To all whom it may concern:

Be it known that we, DAVID J. SEAMAN and CHARLES F. SOMMERS, citizens of the United States, residing in the city of Saginaw, in the county of Saginaw and State of Michigan, have invented new and useful Improvements in Means for Carrying Cardboard Boxes, of which the following is a specification.

10 The object of the invention is to provide means of exceedingly simple and inexpensive nature, enabling cardboard boxes, such as suit-boxes, to be prepared for carrying and to be carried in a very convenient manner.

15 The invention comprises a pair of spaced plates having tangs adapted to be clinched in a wall of a box and buttons about which to wind a cord, which may be passed about the box and between the buttons to receive 20 an ordinary carrying handle between the buttons.

In the accompanying drawings forming part hereof:

25 Fig. 1 is a perspective view of a suit-box equipped with the invention and prepared for carrying;

30 Fig. 2 is an enlarged vertical section through one of the button plates and the portion of the wall of the box in which it is fastened; and

Fig. 3 is a plan view of one of the plates showing the prongs before bending.

The drawing illustrates an ordinary cardboard suit-box 1 consisting of a tray and a 35 telescoping cover. The device is applied to one of the long narrow sides of the cover. It comprises a pair of plates 2 applied in spaced relation to the outside of this wall, at opposite sides of the center of length, at 40 regions about midway between the center and the ends of the box.

The plates are preferably of metal, and have tangs 3 extending from the edges, which can be readily bent and passed through the wall and clinched on the inner 45 side, as seen in Fig. 2.

The central part of each of the plates, in the preferred embodiment, is punched out leaving a hole, and the material thus removed is bent up to form a short neck 4 50 bearing an out-turned flange 5, which is raised just sufficiently above the plate to accommodate a cord beneath the flange or button.

The pair of buttons thus applied to the 55 box receive a cord 6, which is wound beneath the buttons and passed in a suitable manner around the box, tying it, and from one button to the other in a sufficient number of passes 7 to form a strong tension base 60 to receive an ordinary parcel-carrying handle 8. Naturally a cord or cords may be disposed in various specific ways.

The one-piece metal construction of the 65 plate attachments is deemed preferable for most purposes, but I do not limit myself to the precise construction or use of material, and composite or plural-piece forms are contemplated within the scope of the invention.

70 What is claimed as new is:

Box-carrying means comprising a pair of plates designed to be applied in spaced relation to the outside of a box, each plate having tangs adapted to be bent over in the box wall and being further formed with an 75 out-turned flange raised above its upper surface from material removed from a central opening, the two plates on a box adapted to cooperate with a cord substantially as set forth.

DAVID J. SEAMAN.
CHARLES F. SOMMERS.
